Primary Examiner — Brett Miller*Assistant Examiner* — Rani J Abdallah(74) *Attorney, Agent, or Firm* — Cozen O'Connor(57) **CLAIM**

The ornamental design for a bottle, as shown and described.

DESCRIPTION

FIG. 1 is a perspective view of a bottle showing my new design;

FIG. 2 is an exploded perspective bottle of FIG. 1;

FIG. 3 is a front elevation view of the bottle of FIG. 1;

FIG. 4 is a back elevation view of the bottle of FIG. 1; and,

FIG. 6 is left-side elevation view of the bottle of FIG. 1.

The broken lines immediately adjacent the shaded areas represent the bounds of the claimed design while all other broken lines are directed to environment and are for illustrative purposes only; the broken lines in the drawing form no part of the claimed design.

1 Claim, 6 Drawing Sheets(56)
